UNITED STATES PATENT OFFICE.

ARTHUR E. DAVENPORT, OF BROOKLYN, NEW YORK, ASSIGNOR TO THE TEXAS COMPANY, OF NEW YORK, N. Y., A CORPORATION OF TEXAS.

DESIGN FOR A GASOLENE-PUMP STATION.

53,893.

Specification for Design.

Patented Oct. 7, 1919.

Application filed April 30, 1919. Serial No. 293,854. Term of patent 14 years.

To all whom it may concern:

Be it known that I, ARTHUR E. DAVENPORT, a citizen of the United States, and a resident of Brooklyn, Kings county, and State of New York, have invented a new, original, and ornamental Design for a Gasoline-Pump Station, of which the following is a specification, reference being had to

the accompanying drawing, forming a part thereof.

The figure is a view in elevation of a gasoline pump station, showing my new design.

What I claim is:

The ornamental design for a gasoline pump station, as shown.

ARTHUR E. DAVENPORT.
